(57)

CLAIM

The ornamental design for a fender, as shown and described.

DESCRIPTION

FIG. 1 is a top perspective view of a fender showing my new design;

FIG. 2 is a bottom perspective view thereof;

FIG. 3 is a front elevation view thereof, the rear elevation view being an identical image thereof;

FIG. 4 is a left side elevation view thereof, the right side elevation view being an identical image thereof;

FIG. 5 is a top plan view thereof; and,

FIG. 6 is a bottom plan view thereof.

The broken lines shown in the drawings illustrate portions of the fender that form no part of the claimed design.
